UNITED STATES PATENT OFFICE.

GEORGE F. SHEVLIN, OF GLENS FALLS, NEW YORK, ASSIGNOR TO GEORGE F. SHEVLIN & SON, OF GLENS FALLS, NEW YORK, A PARTNERSHIP COMPOSED OF GEORGE F. SHEVLIN, SR., AND GEORGE F. SHEVLIN, JR.

CENTRIFUGAL PULP SCREEN.

Application filed March 31, 1927. Serial No. 179,773.

The present invention relates to an improvement in centrifugal pulp screens and more particularly to the stock distributor or runner element thereof. The invention 5 furthermore is an improvement on the centrifugal pulp screen stock distributor as shown and described in U. S. Letters Patent No. 1,436,411, granted to me, November 21, 1922. The primary object of the invention 10 in this case as in the construction shown and described in the Letters Patent aforesaid is to obtain an even distribution of the stock in forcing or directing the same against the screen. The apparatus as shown in the 15 patent includes a centrally disposed hub, a cylindrical member arranged concentrically with the hub and connected therewith by a series of spaced preferably radially placed blades which extend beyond the cylindrical 20 member, together with a series of vanes, there being a vane associated with that portion of each blade which extends beyond the cylindrical member and in the cylindrical member there are sets of ports or openings 25 making passageways through the same adjacent the inner ends of the vanes, which vanes extend from the top or upper end of the distributor to a point approximately midway thereof. 30 It has been found in the use of a stock distributor or runner of this type that in some instances it operates satisfactorily. In other instances, however, particularly with pulp stock of certain consistencies, the stock or a 35 large portion thereof in passing through the apertures in the cylindrical member is projected directly against the screen without the intervention of the vane. In such instances, of course, the stock is not projected with the 40 force with which it would have been projected through the action of centrifugal force when caused to pass along the surface of the vanes. Consequently, in carrying out the present invention and in order to make 45 the apparatus fully effective with pulp stock of substantially all consistencies, I employ a plurality of deflector plates each associated 50 with one of the vanes so that as the stock passes through the port in the cylindrical member the deflector plate directs the same positively to the corresponding vane, thereby obviating all possibility of any of the stock being projected directly from the port or aperture in the cylindrical member

through which it passes to the screen, and 55 thereby utilizing the vanes to their fullest capacity in imparting swift motion to the stock as the same is delivered therefrom against the screen of the apparatus.

In carrying out the present invention I 60 employ suitable means for adjusting or regulating the passage of the stock from the central compartments to the exterior thereof so that depending upon the consistency of the stock and the speed of the apparatus, an 65 even distribution of the stock and a maximum efficiency of the apparatus may be attained.

The invention will be hereinafter more particularly described in conjunction with 70 the accompanying drawings in which

Figure 1 is a sectional plan on line 1—1, Fig. 2.

Fig. 2 is an elevation of a stock distributor or runner for a centrifugal screen 75 as made in accordance with this invention.

Fig. 3 is a sectional elevation on line 3—3, Fig. 1, and

Fig. 4 is a perspective view on an enlarged scale illustrating one of the deflector plates. 80

Referring to the drawing it will be seen that in carrying out the invention the stock distributor or runner made in accordance therewith is so constructed as to include a hub 10 adapted to be mounted on and connected to a suitable shaft by which it may be turned rapidly. The hub 10 is connected to a cylindrical member 11 by means of a series of blades 12 which are preferably placed in radial positions and divide the space between the hub and the cylindrical member into a corresponding number of compartments or spaces 13. Each blade 12 extends appreciably beyond the cylindrical member as indicated at 14. The top of the distributor is preferably flat as indicated at 15, and the bottom is preferably made concavo-convex as indicated at 16. The blades 12 and their extensions 14 preferably extend from the top to the bottom of the runner. 90 95 100

I also employ a plurality of vanes indicated at 17. There is a vane associated with each of the extended portions 14 of the ribs and an adjacent portion of the cylindrical member 11. These vanes 17 extend from the top or upper portion of the distributor to a point approximately centrally thereof, that is midway of its height. In the wall of the 105

cylindrical member between each of the extensions 14 of the blades, I provide a port indicated at 18. This port is preferably an elongated rectangular slot and is adapted to be covered to a greater or lesser extent by a door 19 so as to determine the area of the port and consequently the amount of stock which under given conditions may pass through the same. Each door is connected 10 to the outer portion of the cylindrical member 11 and provided with slots 20 and bolts 21 by means of which the door is adjustable to position and may be fixed in any suitable place to determine the area of the port or 15 slot which it controls, as hereinbefore stated.

I also employ a plurality of deflector plates each associated with one of the vanes and substantially coextensive therewith and longitudinally of the distributor. As illustrated, in the drawing, the deflector plates are designated at 22 and as shown in Fig. 4, the body of the plate is curved and at one end formed with a flange 23 adapted to fit in a recess or to extend through the upper 20 portion of the corresponding blade extension 14 and to be connected to the top wall of the distributor by means of a rivet or screw 24. At the inner or lower end each deflector plate is formed with a bracket 25, a portion 25 of which is adapted to bear against the adjacent surface of the corresponding blade extension 14 and to be connected thereto by means of bolts 26 or otherwise so as to 30 secure the deflector plate in position in the 35 apparatus.

Below the vanes 17 and the associated deflector plates the cylindrical member 11 is provided in suitably spaced positions with a plurality of holes 27 and also with spaced 40 slots 28. It will furthermore be noted that there is an appreciable space between the lower or inner end of the cylindrical member and the upper face of the concavo-convex bottom plate 16, which space is indicated at 45 29.

In the use of this apparatus the stock is supplied through any suitable means to the compartments 13 between the hub 10 and the cylindrical member 11. From these compartments as indicated by the arrows, the stock passes through the ports 18 and directly against the deflector plates 22 by means of which the stock is directed positively to the corresponding vanes so that 50 none of the stock can be projected directly through the opening or port in the cylindrical member to the screen. Consequently the action of centrifugal force due to the rapid rotation of the distributor or runner 55 imparts a rapid flow to the stock causing the same as it leaves the runner to be projected with considerable force against the screen. This action as will be understood, applies to the lighter portion of the stock as the apparatus utilized for this purpose is in the upper 60 65

portion of the distributor. The heavier portion of the stock passes in a customary manner toward the bottom of the compartments in the cylindrical member and passes through the openings or ports 27 and 28 therein and is projected against the screen by the extensions 14 of the blades. Furthermore, that a portion of the stock which is not delivered in either of the manners to which reference has been made, is permitted to pass by way of the space 29 to the upper surface of the bottom of the distributor and thence to the pipe lines or other means through which the slivers may be discharged. 70 75 80

I claim as my invention:

1. In a centrifugal pulp screen, a stock distributor comprising a hub, a cylindrical member, blades extending from the hub to and beyond the cylindrical member, a plurality of vanes each associated with the outer portion of the cylindrical member and an adjacent portion of one of the blades, and a plurality of deflector plates each associated with a vane and so constructed and secured in position as to positively direct the passage of stock to the corresponding vane. 90

2. In a centrifugal pulp screen, a stock distributor comprising a hub, a cylindrical member, a plurality of blades extending from the hub to and beyond the cylindrical member, a plurality of vanes each associated with the outer portion of a blade and the adjacent portion of the cylindrical member, there being a port through the wall of the cylindrical member between each of the parts of the blades extending beyond the same, means for controlling the discharge of stock through the said ports, and a plurality of deflector plates each associated with one of the said vanes and adapted to direct the flow of the stock as the same passes through one of the said ports to the corresponding vane. 95 100 105

3. In a centrifugal pulp screen, a stock distributor comprising a hub, a cylindrical member, a plurality of blades extending from the hub to and beyond the said cylindrical member, the cylindrical member having a series of ports therein, each port being placed adjacent one of the extended portions of a blade, a corresponding number of doors each controlling a port, means for adjusting the position of each door to determine the area of the corresponding port, a plurality of vanes each associated with an outer portion of one of the blades and the adjacent portion of the cylindrical member, and a plurality of deflector plates each adapted to direct the flow of stock as the same passes through the corresponding port 110 115 120 125 to the corresponding vane.

4. In a centrifugal pulp screen, a stock distributor comprising a hub, a cylindrical member concentric therewith, a plurality of blades extending from the hub to and be- 130

yond the said cylindrical member, there being a plurality of ports in the wall of the cylindrical member, each port being adjacent a blade, a plurality of doors each associated with one of the ports, means for adjusting each door to position to determine the area of the corresponding port, a plurality of vanes each extending from the top of the distributor to a point approximately midway of its length and associated with the outer portion of a blade and the adjacent portion of the wall of the cylindrical member, the said ports and doors being also substantially coextensive of the extent of the said vanes, and a plurality of deflector plates each associated with a corresponding vane and adapted to direct the flow of the stock as the same passes through the corresponding port to the corresponding vane.

5. In a centrifugal pulp screen, a stock distributor comprising a hub, a cylindrical member concentric therewith, a plurality of blades extending from the hub to and beyond the said cylindrical member, there

being a plurality of ports in the wall of the cylindrical member, each port being adjacent a blade, a plurality of doors each associated with one of the ports, means for adjusting each door to position to determine the area of the corresponding port, a plurality of vanes each extending from the top of the distributor to a point approximately midway of its length and associated with the outer portion of a blade and the adjacent portion of the wall of the cylindrical member, the said ports and doors being also substantially coextensive of the extent of the said vanes, and a plurality of deflector plates, each deflector plate being curved and secured in position to the outer portion of one of the said blades so as to extend over a corresponding port with which it is substantially coextensive whereby stock in passing through the said port is deflected directly to the corresponding vane.

Signed by me this 16th day of March, 1927,

GEO. F. SHEVLIN.
